UNITED STATES PATENT OFFICE.

FRANK R. McBERTY, OF EVANSTON, ILLINOIS, ASSIGNOR TO THE
WESTERN ELECTRIC COMPANY, OF CHICAGO, ILLINOIS, A COR-
PORATION OF ILLINOIS.

SERVICE-METER FOR TELEPHONE-LINES.

SPECIFICATION forming part of Letters Patent No. 755,308, dated March 22, 1904.

Application filed July 16, 1900. Serial No. 23,729. (No model.)

To all whom it may concern:

Be it known that I, FRANK R. McBERTY, a citizen of the United States, residing at Evanston, in the county of Cook and State of Illinois, have invented a certain new and useful Improvement in Service - Meters for Telephone-Lines, of which the following is a full, clear, concise, and exact description.

My invention relates to a telephone toll-line system, and has for its object to provide a toll device, such as a service-meter and circuits therefor, associated with each line of a telephone system, whereby a charge may be made for each use of a subscriber's telephone-line in which the subscriber is actually placed in communication with the party called for.

A further object is to provide an automatically-operated signal at the substation of the telephone-line, whereby the subscriber at that station may be informed when the connection called for has been obtained and the called party has answered.

One feature of my invention consists of a magnet connected with a telephone-line at the substation thereof and blocking mechanism controlled by said magnet for rendering inoperative the telephone apparatus at the substation, whereby the use of such telephone apparatus may be prevented, a source of current at the central office adapted to energize said magnet, whereby said blocking mechanism may be actuated, means made operative in completing connection between said telephone-line and another line for connecting said source of current with the line, a toll device at the substation adapted to be manually operated, and a releasing appliance actuated in the operation of said toll device for counteracting said blocking mechanism, whereby the substation apparatus may be made operative. I preferably provide an electromagnetic switch at the central office for controlling the application of the aforesaid source of current to the calling-line, said electromagnetic switch being controlled by a device responsive to the flow of current in the called line, so that when the called subscriber takes his telephone from its switch-hook to respond to the call the

change in the electrical condition of the called line thus produced will cause the actuation of 50 said electromagnetic switch at the central office, whereby the magnet at the calling-subscriber's station is energized to actuate the blocking mechanism aforesaid, and the calling-subscriber's telephone apparatus is thus rendered inoperative. The calling subscriber is therefore compelled to actuate his toll device in order to restore the operative condition of his telephone apparatus.

A further feature of my invention consists 60 in the provision of an electromagnetic signal-indicator at the substation of the calling subscriber, with a source of current and a switch associated with the operator's plug-circuit at the central office for controlling the application 65 of current to said signal-indicator, whereby a signal may be indicated at the substation by the operation of said switch. The switch at the central office may be operated electrically and controlled through the agency of the 70 telephone-switch at the called station, whereby a signal may be displayed at the calling-station when the called subscriber responds notifying the calling subscriber that the desired connection has been obtained and that 75 he must actuate his toll device in order to use his telephone for conversation. The signal-indicator at the calling-station may be a target moved by the armature of the magnet 80 which controls the blocking mechanism.

I will describe my invention more particularly by reference to the accompanying drawing, which is a diagram illustrating by means of conventional symbols two telephone-lines extending from substations to a central office, 85 together with the central-office apparatus for connecting said lines together, the system being provided with the service-measuring apparatus of my invention and the auxiliary signal device therefor.

The subscriber's apparatus at each of the substations A B is of the usual type with the exception of the toll-counting device and its associated mechanism for "blocking" or rendering inoperative the telephone apparatus. 95 Each telephone-line consists of two limbs 12

terminating at the central office in line-springs a' a'' , respectively, of a spring-jack a . The usual line-signal is associated with each telephone-line at the central office for indicating calls. A cut-off relay b is also associated with each line, being connected in a grounded branch from the third contact or test-ring a^3 of the spring-jack, said relay being adapted when energized to disconnect the line-signal apparatus from the line. An answering-plug c and a connecting-plug d are furnished at the central-office switchboard C for connecting any two lines together, said plugs being adapted to be inserted in the spring-jacks of the lines and having a complete circuit for telephone-currents between them, said circuit being formed by conductors 3 4 and 5 6, which lead in pairs to the poles of the battery e through the windings of a repeating-coil in the usual manner. The conductors 4 and 6 include the magnet-windings of supervisory relays f g , which control, respectively, supervisory signal-lamps f' g' . One pole of the battery e is grounded, and the supervisory signal-lamps f' g' are included in conductors 8 9, respectively, leading from the other pole of said battery e to sleeve-contacts c^3 d^3 of plugs c d , respectively. These sleeve-contacts of the plugs register with the grounded test-rings a^3 of the spring-jacks. Shunt-circuits 10 11 are provided about the signal-lamps f' g' , said shunt-circuits being controlled by switch-contacts operated by the supervisory relays f g , respectively. When either of said shunt-circuits is closed, its corresponding signal-lamp is thereby deprived of current. The conductors 5 6 of the plug-circuit terminate, respectively, in the tip and ring-contacts d' d'' of the plug d . Similarly the conductors 3 4 of the plug-circuit are normally connected with the tip and ring contacts c' c'' of the plug c . A double-pole switch h is provided, however, whereby the connections of the conductors 3 4 are reversed, said switch being adapted to be operated by an electromagnet h' . The magnet h' is provided with two windings. One of said windings, h^2 , of low resistance, is included in series in the conductor 11, which shunts the signal-lamp g' and is controlled by the supervisory relay g . The other winding, h^3 , of high resistance, is serially included in a conductor 12, which forms a second shunt around the signal-lamp g' and is controlled by the relay-armature h^4 of the magnet h' itself. When the supervisory relay g is energized, the effect is first to close the shunt 11 around the supervisory signal-lamp, thereby causing the lamp to be deprived of current and the light extinguished. Since the shunt 11 thus closed includes the winding h^2 of the magnet h' , said magnet will be energized, attracting its armature h^4 and also operating the double-pole switch h to reverse the connections between the battery e and contacts of the answering-

plug c . The armature h^4 being drawn up closes the circuit 12, which includes the retaining-winding h^3 of the magnet h' , whereby said magnet is supplied with current and maintained energized independently of the circuit 70 11, controlled by relay g .

Turning now to the apparatus at the substations of the system, I will describe in detail the apparatus at substation A. The apparatus at the other stations may be identical.

The toll device shown in the drawing is a connection-register or service-meter and consists of a train of counting-wheels i , including a star-wheel, the teeth whereof are adapted to be engaged by the pallets of an oscillating escapement-lever k . The counting-train may thus be moved step by step, a full beat or complete oscillation of the lever k being necessary to advance the counting-train the full distance from one figure of the dial to the next. A spring k' is fastened to the actuating-lever k , tending to rock said lever in a clockwise direction to cause the initial movement of the escapement-pallets carried by said actuating-lever. A subsequent movement of the lever k in a reverse direction will complete the registration. A manually-operated plunger or push-key l is associated with the actuating-lever k , whereby said lever may be moved in a contra-clockwise direction. The plunger l preferably is not mounted upon the actuating-lever, but is capable of movement independently thereof and is normally maintained in its outer position by means of a spring l' . The plunger l preferably carries a movable switch-contact l'' , which normally rests against a stationary contact l''' , engagement between said contact parts $l'' l'''$ being broken when said plunger l is pushed in to move the actuating-lever k of the toll-counter. The contacts $l'' l'''$ are serially included in the telephone-circuit, whereby said circuit is broken momentarily when the subscriber pushes in on the plunger l to operate his toll-counter, the plunger moving back again under the influence of spring l' to reestablish the circuit as soon as pressure is removed therefrom. The object of this arrangement is to prevent the subscriber from keeping the plunger l permanently pushed in with the design of preventing the operation of his toll-counter.

A polarized electromagnet p is associated with the toll-counting mechanism, the windings of said magnet being connected in the branch of the line which leads through the subscriber's telephone talking apparatus. The winding of the magnet is preferably shunted by a comparatively high non-inductive resistance to diminish its impedance to telephone-currents. This polarized magnet p has a centrally-pivoted tilting armature m , which carries a latch or detent m' , adapted to engage and hold the end of the actuating-lever k when the same has been pushed in by the plunger l . The armature m also carries a movable target 130

n, adapted to be displayed in an opening in a shield *n*² when the armature is tilted to one side in a clockwise direction. A contact-point *m*² is associated with the latch *m'*, said latch 5 being normally separated from said contact, but being adapted to make engagement therewith when the polarized armature *m* of the magnet is moved in a clockwise direction. When the actuating-lever *k* is pushed in by 10 means of the plunger *l*, the end of said lever is adapted to engage the latch *m'* and separate the same from the stationary contact *m*². Further movement of the lever causes the same to be caught and held by the catch. A movement 15 of the centrally-pivoted armature *m* in a contra-clockwise direction serves to raise the catch *m'* from the end of the actuating-lever *k*, the lever as soon as it is released from said catch being moved out from under the 20 catch by the spring *k'*. A centralizing spring *o* serves to yieldingly maintain the armature *m* in a central position. To recapitulate, when the armature *m* is tilted in a contra-clockwise direction the catch *m'* is lifted off the end of 25 the lever *k*, so that said lever is drawn over by the spring *k'* until it strikes the end of the plunger *l*. This movement of the lever effects a half-registration of the counting-train *i*. The armature *m* is now free to move in a 30 clockwise direction and will make such a movement under the influence of suitably-directed current flowing through the coils of the polarized magnet *p*. Contact will then be established between the catch *m'* and the contact-point *m*², and the target *n* will simultaneously be displayed before the opening in the shield *n*². The contacts *m'* *m*² control the local bridge conductor 13, which is adapted 35 when closed to short-circuit the telephone apparatus at the substation, whereby such telephone apparatus may be rendered inoperative.

The use of the telephone apparatus at any substation to carry on conversation over the telephone-line may be effectually prevented 40 or blocked by the mechanism which is operated by the polarized magnet *p*, said magnet being adapted to be energized by current which may be applied at the central office. In the particular system illustrated current to 45 operate the blocking mechanism at the substation is applied through the agency of the electromagnetic switch *h* at the central office, which switch is controlled by apparatus at the called station.

50 The operation of the system is as follows: Assuming that the subscriber at substation A desires to communicate with the subscriber at substation B, he takes his receiving-telephone from its switch-hook and permits the 55 telephone-switch to close the circuit of the line in the usual manner, providing a path for current in the line from the central source, which excites the line-relay and causes the illumination of the line-signal lamp. On seeing the call-signal thus displayed the opera-

tor inserts the answering-plug *c* of a pair of plugs into the answering-jack *a* of the calling-line. This act of the operator closes a local circuit through the cut-off relay to remove the line-signal apparatus from the circuit. 70 At the same time the battery *e* of the plug-circuit is connected in a bridge between the limbs 1 2 of the telephone-line by way of the cord-strands 3 4 of the plug-circuit. Since the circuit of the telephone-line is closed at 75 the substation by the telephone-switch, the circuit from battery *e* over the line is completed. This circuit includes the winding of the supervisory relay *f*, which is included in the cord strand 4 of the plug-circuit, whereby 80 said relay is energized and closes the shunt-circuit 10 about the supervisory signal-lamp *f'*, the signal-lamp remaining dark. The polarized magnet *p* being included in the line-circuit at the substation A receives current 85 from battery *e*, the circulation of current in the circuit being in the proper direction to tip the armature *m* of said magnet in a contra-clockwise direction, whereby the actuating-lever *k* of the toll-counting mechanism is released, as before explained, and is drawn over by spring *k'*, effecting a half-registration. The central-office operator now communicates 90 with subscriber A by telephone in the usual manner and inquires the number of the station with which connection is desired. Upon receiving this information she inserts the other or connecting plug *d* of the pair into the spring-jack of the line wanted and signals the called station in the usual way. Upon 95 connection of the plug *d* with the spring-jack of the called line circuit is completed from the grounded battery *e*, through the conductor 9 and supervisory signal-lamp *g'*, to the sleeve-contact *d*³ of the plug *d*, and thence to ground 100 by way of the called subscriber's cut-off relay. When the subscriber at the called station takes his telephone from its switch-hook to answer the call, the telephone-switch closes the circuit of the called line, whereby the supervisory relay *g* in the conductor 6 of the plug-circuit receives current and draws up its armature. The shunt-conductor 11, including the winding *h*² of the magnet *h*', is thus 105 closed, energizing said magnet. The resistance of this shunt-conductor 11 is so low that the lamp *g'* is deprived of current and is extinguished. The magnet *h*' being excited draws up its armature *h*⁴, thereby closing the circuit 12, which includes the retaining-winding *h*³, whereby said magnet is continuously supplied with current as long as the plug *d* remains in the spring-jack of the called line. The excitation of the magnet *h*', which is thus 115 consequent upon the removal of the telephone at the called station from its hook in response to the call, operates the double-pole switch *h*, reversing the connection of battery *e* with the calling-line, and the reversal of the current through the polarized magnet *p* at the 120 125 130

substation A of the calling-line causes the armature m of said relay to tip in a clockwise direction. This movement of the armature m accomplishes two results: First, it closes 5 the short circuit 13 about the telephone apparatus, rendering said apparatus inoperative and blocking communication between the stations A and B, and, second, it moves the target n before the opening in the shield n^2 . The 10 display of the target n indicates to the calling subscriber that the called party has answered and that he must push in on the plunger l to operate his toll-counter in order that he may use his telephone. When the plunger 15 l is pushed in, it completes the registration previously initiated when the central-office operator plugged into the line in answering the call and also releases the catch m' from its contact m^2 , thus breaking the short circuit 13 20 and permitting the use of the telephone.

I claim as my invention—

1. The combination with a calling and a called line and switching apparatus for uniting them, of a toll device at the substation of the 25 calling-line adapted for manual operation, a blocking device, a telephone-switch at the substation of the called line, means controlled by said telephone-switch for setting the blocking device, and a releasing appliance actuated in 30 the operation of the toll device for counteracting or restoring the blocking device, substantially as set forth.

2. In a telephone-exchange system, the combination with a calling and a called line extending from substations to a central office, of link conductors at the central office for uniting said lines, a polarized magnet connected with the calling-line and a signal-indicator operated thereby, a source of current, 40 a reversing-switch at the central office controlling the flow of current in the calling-line, a circuit for operating said reversing-switch established in making connection with the called line, and a switch at the called station 45 controlling said circuit; whereby the response of the called subscriber is indicated by the display of said signal at the calling-station.

3. In a telephone-exchange system, the combination with a telephone-line extending from 50 a substation to a central office, of an operator's answering-plug at the central office for making connection with said line in response to a call, a connecting-plug and a cord-circuit uniting the same with the answering-plug, said 55 connecting-plug being adapted to make connection with another telephone-line, a magnet at the calling-station connected with the telephone-line thereof, a signal-indicator operated by said magnet, a source of current, an electromagnetic switch at the central office for controlling the flow of current through said magnet, and a circuit for controlling said electromagnetic switch, established by connection of the connecting-plug with the called line, 60 substantially as set forth.

4. In a telephone-exchange system, the combination with two telephone-lines extending from substations to a central-office switchboard, of means at the central office for connecting the lines together, a signal-indicator 70 at the substation of one of the lines, means controlled by a switch at the central office for actuating said signal-indicator, electromagnetic mechanism controlled by the flow of current in the other line for operating said switch, 75 and means at the substation of said last-mentioned line for determining the flow of current therein, substantially as set forth.

5. In a telephone-exchange system, the combination with two telephone-lines extending 80 from substations to a central-office switchboard, of an operator's plug-circuit for connecting the lines together in response to a call from substation of one of said lines, a magnet and means controlled by said magnet 85 for interfering with the transmission of telephonic voice-currents between the telephones at the respective stations, whereby telephonic communication between said stations is prevented, a source of current adapted to energize 90 said magnet, an electromagnetic switch controlling the flow of current through said magnet, and a circuit controlling said electromagnetic switch, established by the connection of the plug-circuit with the called line, substantially as set forth.

6. In a telephone-exchange system, the combination with two telephone-lines extending from substations to a central-office switchboard, of means at the central office for connecting the lines together in response to a call from the substation of one of said lines, a magnet and blocking mechanism controlled by 100 said magnet for interfering with the transmission of telephonic voice-currents between the 105 telephones at the respective stations, whereby telephonic communication between said stations may be prevented, an electric circuit including said magnet with a source of current, a toll-counter at the substation of the calling-line adapted to be manually operated, a device actuated in the operation of said toll-counter for controlling said blocking mechanism, whereby the operative condition of the system may be restored upon the operation of said 110 toll-counter, and means controlled through the agency of a switch at the called station for changing the electrical condition of the circuit including said magnet, substantially as set forth.

7. The combination with a telephone-line extending from a substation to a central office and a pair of plugs and a plug-circuit for connecting said line with another line, a polarized electromagnetic switch at the substation of the first-mentioned line and blocking mechanism controlled by said magnet for rendering the telephone at said station inoperative, said magnet being adapted to actuate said blocking mechanism only when traversed by current of 115 120 125 130

a given polarity, a toll-counter and a device associated with said toll-counter and actuated in the operation thereof for counteracting said blocking mechanism, a battery connected 5 with the calling-line at the central office, the normal connection of said battery with the line being opposite to that required for the actuation of said blocking mechanism, and means, controlled through the agency of a 10 switch at the called station, for reversing the connection of said battery with the calling-line, whereby said blocking mechanism is operated and the calling subscriber compelled to operate his toll-counter in order to use his 15 telephone, substantially as set forth.

8. The combination with a telephone-line and a service-meter therefor, of a blocking device adapted to prevent the use of the telephone-line and a manually-operated appliance 20 controlling said meter and said blocking device to render the blocking device ineffective, a signal at the substation of the line and actuating-circuits therefor associated with the line, an electromagnetic switch controlling 25 said actuating-circuits, and circuit connections of the magnet of said switch made operative in establishing connection with the called line; substantially as described.

9. The combination with a telephone-line 30 and a service-meter therefor, of a manually-operated part at the substation adapted to actuate the service-meter, a blocking device for preventing the use of the telephone and a controlling-magnet for said blocking device, 35 said blocking device being also controlled by said manually-actuated part to render the blocking device inoperative in the movement of the service-meter, an electrically-controlled signal at the substation and an electric circuit 40 controlling said magnet of the blocking device and said signal, and a switch made operative in establishing connection with a line called for closing said circuit; whereby the establishment of connection with the called 45 station is signaled to the calling-station and the telephone at the latter station is blocked until the call is registered, as described.

10. The combination with a calling and a called line extending from a substation to a 50 central office and link conductors for uniting said lines, of a visible signal at the calling-station, an electromagnetic switch at the central office and a source of current controlled thereby for operating said visible signal, a 55 switch at the called station, and means controlled by said last-mentioned switch for operating said electromagnetic switch, as set forth.

11. In combination two telephone-lines and 60 link conductors for uniting them, a visible signal at the calling-station and a circuit therefor, an electrically-actuated switch controlling said circuit, said switch being itself controlled by the telephone-switch at the called station, and 65 an electric locking device on said switch actu-

ated in the initial response of the switch adapted to prevent its further operation, the circuit of said locking device being completed in registering contacts of the link conductor and the called line; whereby the signal at the calling-station is operated in the use of the telephone at the called station, but is thereafter placed out of control of the called station during the continuance of the connection, as described. 70

12. In combination two telephone-lines and link conductors uniting them, a service-meter of the calling-line and a blocking mechanism controlling the use of the telephone at the calling-station, a manually-operated part for 80 actuating said service-meter and said blocking device to render the blocking device inoperative, an electromagnet actuating the blocking device to prevent the use of the telephone, and a circuit of said electromagnet, an electrically-actuated switch controlling the circuit of said electromagnet, said switch being itself controlled by the telephone-switch of the called station, and a locking-circuit of said switch closed when the switch is actuated, said 85 locking-circuit being completed in registering contacts associated with the link conductor and the called line; whereby the blocking mechanism of the calling-line is controlled from the called station at the initial movement of the telephone-switch at the latter station, but is free from such control thereafter during the existence of the connection, as described. 90

13. In an automatic connection-registering 100 system for telephone-exchanges, the combination with the central-office apparatus, of means for automatically altering the flow of current in the calling-subscriber's line controlled from the called-subscriber's station, and at the calling-subscriber's station, registering apparatus comprising a relay connected to line, the armature of which is designed to be operatively actuated by current of predetermined 105 character, a controlling-circuit extending to the instrument controlled, adapted to be opened and closed by said relay, whereby said instrument may be rendered temporarily inoperative, a meter device and means for actuating the meter and for restoring the controlled instrument to service, substantially as set forth. 110

14. In a telephone system, the combination with the calling-subscriber's instrument, of a polarized relay device adapted, when energized by current of one polarity, to render the instrument temporarily inoperative, a registering appliance, means for jointly restoring the instrument to service and for actuating the registering appliance, central-office 115 apparatus for effecting the desired connections, and in addition thereto, automatically-actuated circuit-controlling apparatus governed by the called subscriber, adapted to supply current of the requisite polarity to 120 125 130

the said relay device, substantially as set forth.

15. In combination with a telephone-exchange system, a reversing-relay provided in the answering side of the cord-circuit, said relay being automatically controlled by the called subscriber, and at the calling-subscriber's instrument, a polarized relay adapted to respond to current from the relay and temporarily render the instrument inoperative, a call-registering appliance and means for actuating the latter and for restoring the subscriber's instrument to service, substantially as set forth.

15 16. In combination with a telephone system, a reversing-relay provided in the answering side of the operator's cord-circuit, said relay being automatically controlled by the called subscriber, under normal conditions, a nullifying-key connected with said relay, and at the calling-subscriber's station, a polarized connection-registering appliance adapted to be actuated by the reversing-relay, substantially as set forth.

25 17. In combination with a telephone-exchange system, a reversing-relay in the answering side of the cord-circuit, means for automatically energizing the same when the called subscriber answers, and at the calling-subscriber's station, a telephone instrument, a polarized electromagnet, an armature, a controlling-circuit governed thereby, adapted to shunt the subscriber's transmitter, a counting-train and manually-controlled means for jointly actuating the counting-train and for breaking the shunt-circuit, substantially as set forth.

18. In a telephone-exchange system, the combination with a subscriber's instrument, of a relay device adapted to shunt the transmitter-circuit thereof, a counting-train, manually-controlled means for jointly actuating the counting-train and opening the shunt-circuit, central-office apparatus and in the answering side of the cord-circuit, means controllable from the called-subscriber's station for actuating said relay device to close the shunt-circuit of the transmitter, substantially as set forth.

50 19. The combination with a calling and a called line and apparatus at a central office for uniting them, of a toll device for the calling-line, an automatic blocking device adapted when actuated to render the system inoperative for telephonic communication between the calling and the called stations, apparatus controlled at the called station for setting said blocking device, and means actuated in the operation of said toll device for restoring to their 55 normal condition the parts affected by said blocking device, whereby the operative condition of the system is re-established.

20. The combination with a calling and a called line and means at the central office for 65 uniting them, of a toll device at the substa-

tion of the calling-line adapted for manual operation by the subscriber, a blocking device adapted when actuated to prevent telephonic communication between the calling and the called stations, means controlled through the agency of the telephone-switch at the called station for operating said blocking device, and means controlled in the operation of the toll device for counteracting or making inoperative said blocking device.

75 21. The combination with a calling and a called line and apparatus at a central switchboard for uniting them, of a toll device at the substation of the calling-line, an electromagnetic switch at the central office adapted to 80 change the electrical condition of the calling-line, an electromagnet at the calling-substation responsive to the change produced by said electromagnetic switch, mechanism controlled by said electromagnet for rendering the apparatus at the calling-station inoperative for telephonic purposes, means controlled at the substation of the called line for setting said electromagnetic switch, and means controlled in the actuation of said toll device for 90 restoring said switch.

22. The combination with a telephone toll-line extending from a substation to a central office, of a toll device at the substation adapted for manual operation by the subscriber, a polarized electromagnet associated with the toll device and connected with the telephone-line, an armature for said electromagnet controlling the operation of the toll device, said armature also controlling a switch for rendering the telephone apparatus inoperative, a plug-circuit at the central office adapted to connect the toll-line with another line in response to a call initiated from the toll-line, a source of current in the plug-circuit, a blocking-switch controlling the application of current to the toll-line and adapted when actuated to direct current over the toll-line to energize said polarized electromagnet, whereby the armature of said magnet is moved to 105 release the toll device and simultaneously to render the telephone apparatus at the calling-substation inoperative, a switch at the called station, a supervisory relay for the called line at the central office, controlled by said switch 110 at the called station, a circuit for the blocking-switch controlled through the agency of said supervisory relay, and means, controlled in the operation of the toll device at the calling-substation, for reversing the operation of 115 the armature of the electromagnet, to re-establish the operative condition of the telephone apparatus, substantially as set forth.

In witness whereof I hereunto subscribe my name this 5th day of July, 1900.
